UNITED STATES PATENT OFFICE.

SANFORD E. CLINE, OF GREENSBURG, LOUISIANA, ASSIGNOR OF ONE-HALF TO F. M. THOMSON, OF INDIANAPOLIS, INDIANA.

PUMP PISTON OR PLUNGER.

Application filed September 29, 1923. Serial No. 665,581.

To all whom it may concern:

Be it known that I, SANFORD E. CLINE, a citizen of the United States, residing at Greensburg, in the county of Decatur and 5 State of Indiana, have invented certain new and useful Improvements in Pump Pistons or Plungers; and I do hereby declare the following to be a full, clear, and exact description of the invention, such as will 10 enable others skilled in the art to which it appertains to make and use the same.

The present invention relates to pistons or plungers, especially those used in pump cylinders, and aims to provide a pump piston or "sucker" provided with novel and 15 improved packer means of metal or other suitable material, which will have a longer life than leather, rubber and similar packers as now used, and to provide for greater 20 efficiency and less annoyance, it being well known that the leather, rubber and similar packers wear out quickly, especially when subject to constant or hard use.

Another object of the invention is the 25 provision of such metal or similar packer means having sections so assembled that the movement of the piston or plunger in one direction (usually downward) is free and easy, with minimum friction between 30 the piston and cylinder, and whereby said sections are caused to snugly fit the cylinder when the piston moves in the opposite direction so as to prevent leakage between the piston and cylinder.

35 A further object is the provision of a piston or plunger of the kind indicated, wherein the packer means will also provide a valve permitting the flow of the liquid past the piston when it moves in one direction, or downwardly, so that the packer and valve comprise a single device, one section of the packer providing the valve.

With the foregoing and other objects in view, which will be apparent as the description 45 proceeds, the invention resides in the construction and arrangement of parts, as hereinafter described and claimed, it being understood that changes can be made within the scope of what is claimed, without departing from the spirit of the invention.

The invention is illustrated in the accompanying drawings, wherein—

Figure 1 is a side elevation of the im-

proved pump piston, showing the cylinder in section.

Fig. 2 is a plan view of the piston.

Fig. 3 is a vertical section on the line 3—3 of Fig. 2.

Fig. 4 is an elevation of one part or section of the piston.

Fig. 5 is an elevation of the other part or section of the piston.

Fig. 6 is a side elevation showing the improvement incorporated in a modified way, in an ordinary pump piston or sucker.

Fig. 7 is a section on the line 7—7 of Fig. 6.

Fig. 8 is a section on the line 8—8 of Fig. 6.

Fig. 9 is an elevation of one section of 70 the packer of the device shown in Figs. 6, 7 and 8.

In the construction shown in Figs. 1 to 5, inclusive, the piston is not of the conventional form, as shown in Figs. 6 to 9, 75 inclusive, but comprises a disk 7 having the marginal offset portion or step 8. As shown, the portion 8 extends upwardly, which is the arrangement when the piston is used in a vertical pump cylinder for lifting or raising the water or other liquid therein.

The lower end of the pump or sucker rod 11 is attached to the piston in any suitable manner, and as shown, the lower 85 end of the rod is screw-threaded into the disk 7 at the center thereof, and a lock nut 9 is threaded on the rod and bears against the disk 7, with the portion 8 surrounding and spaced from said nut.

The packer means of the piston includes the cylindrical rim or packer portion 14 extending from the edge of the portion 8, and projecting upwardly, as shown, or in the same direction from the disk 7 as the 95 portion 8. The portion 14 is an integral part of the piston proper, and is adapted to snugly fit the inner surface of the cylinder, with the portion 14 extending in the direction in which the liquid is moved by 100 the piston, in the manner of the ordinary leather, rubber or similar packer. The offset portion or step 8 forms a shoulder 15 facing the edge of the portion 14.

The piston, including the disk 7, offset 105 portion 8 and packer or rim portion 14, is

divided into two sections 12 and 21, with the division 16 being disposed in a single oblique or inclined plane intersecting the axis of the piston intermediate the planes 5 of the disk 7 and edge of the portion 14. The two sections of the piston are arcuate with their adjacent ends cut obliquely to abut and overlap, as seen in Figs. 1 and 3. By this arrangement, with the pump rod 11 10 secured to the section 21 of the piston, the section 12 is free from said rod, and is capable of longitudinal movement relatively to the rod 11 and section 21. Consequently, when the piston moves downward, the section 12 can be displaced upwardly relatively to the section 21, as shown in broken lines in 15 Fig. 1, to permit the liquid to pass, and said section 12 therefore provides the valve of the piston, without requiring a separate 20 or additional valve.

When the rod 11 is moved upwardly, the valve section 12 of the piston will settle down on the inclined surface 16 of the section 21, and the pressure of the head of 25 liquid on the section 12 will force it with a wedge fit between the section 21 and the wall of the cylinder, the inclined surface 16 of the section 21 shifting the section 12 toward and against the cylinder wall when 30 the section 12 moves downwardly relatively to the section 21, with a cam action between the sections. As a result, the two sections will be brought into registration, and the 35 cam action between them will cause the sections to tightly fit the cylinder wall when the piston is raised, thereby providing the packer means to prevent leakage between the piston and cylinder.

In order to limit the displacement of the 40 valve section 12, a stop 10 is carried by the rod 11 above the disk 7, and, as shown, is of circular form, and has the arms or spokes 17 radiating from a hub 18 screw-threaded on the rod, with the outer ends of said arms 45 or spokes connected to an annular rim or ring 19. A lock nut 20 is threaded on the rod and bears against the hub 18 to maintain the adjustment of the stop 10, which is disposed within and surrounded by the 50 packer portion 14, spaced from the shoulder 15 with the sections 12 and 21 in registering position. When the valve section 12 is moved to open position, as seen in broken lines in Fig. 1, the shoulder 15 of the section 12 will strike the stop 10, thereby 55 limiting the separation of the sections, and keeping the section 12 in a position so that it will quickly move back to closed position when the piston is reversed and moved upwardly.

With such construction, although the piston is divided or split into two parts, it combines therewith as an integral unit, the packer means and valve without separate 60 valve and packer being required. The con-

struction is not only capable of enduring considerable wear and hard usage, but is also simple and inexpensive to manufacture, there being but few parts which can be readily made and assembled.

70

Figs. 6, 7, 8 and 9 illustrate the improvements embodied, in a modified way, in a pump piston or sucker of conventional construction, including the annular valve seat 7' having the lower outstanding flange 8', a ring 9' screw-threaded on the valve seat, and an arched spider 10' integral with said ring and having its hub or central portion screw-threaded on the lower end of the pump or sucker rod 11'. A valve 12' bears 75 on the seat 7' and is retained within the spider or cage 10', permitting the liquid to flow upwardly through the central opening of the piston or plunger when same is moved downwardly. Such construction is 80 of the conventional form, and a leather, rubber or similar packer is usually clamped between the flange 8' and ring 9', to prevent leakage between the piston and cylinder. However, in embodying the improvements 85 in such a piston, a metal packer 13' is used, which is of substantially the same shape as the ordinary cup packer of leather, rubber or similar flexible material, whereas the packer 13' is of lead, aluminum or other 90 suitable metal or alloy. The packer 13' comprises the cylindrical portion or rim 14' surrounding the ring 9' and spider 10' and fitting the inner surface of the pump cylinder, and an inturned flange 15' at the 95 lower edge of the portion 14' disposed between the flange 8' and ring 9' to assembly the packer with the body of the piston.

The packer 13' is split or divided into two sections, and the division or split is 100 disposed in an oblique or inclined plane intersecting the axis of the piston and packer intermediate the edges of the portion 14', and arranged at an acute angle with such axis, as at 16'. The packer is thus divided 105 into two sections 12'' and 21', corresponding to the sections 12 and 21 of the first form hereinbefore described, with the ends of the sections inclined to abut in overlapping relation. The portion of the flange 15' carried by the section 21' is thicker than the portion of such flange carried by the section 12'', whereby the portion of the flange 15' of the section 21' can be clamped 110 tightly between the flange 8' and ring 9' of the piston or plunger, to make the section 21' rigid with the rod 11', the same as in the first form, while the portion of the flange 15' carried by the section 12'' being thinner is loose between the flange 8' 115 and ring 9' to permit of limited longitudinal or vertical movement of the section 12'', whereby it acts, in a modified manner, similar to the valve section 12 of the first form. Thus, when the piston is moved 120

125

130

downwardly, the section 12" can move upwardly relatively to the section 21' of the packer, the ring 9' serving as a stop, similar to the stop 10, for limiting the upward displacement of the section 12", and the section 12" being removable slightly from the wall of the cylinder, to constitute a secondary valve. When the piston is moved upwardly, the section 12" will wedge down between the inclined ends of the section 21' and the wall of the cylinder, there being a cam action between the sections of the packer, whereby the ends of the packer are fitted tight together, and the packer sections fitted against the cylinder wall, to prevent leakage between the piston and cylinder wall. The construction and operation of the packer 13' are therefore somewhat the same as the construction and operation of the piston shown in Figs. 1 to 5, inclusive, the packer 13' being such that it can be used with the ordinary piston or plunger. By the use of the packer 13', the advantages of the present invention can be incorporated in the pump pistons or plungers now in use, or, such pistons or plungers can be replaced by the device first described herein.

Having thus described the invention, what is claimed as new is:—

30 1. A piston having a cylindrical packer portion divided in a single oblique plane into two sections, one of which is loose to be displaced relatively to the other section when the piston is moved in one direction and to have a wedge fit between the last named section and cylinder wall when the piston is moved in the opposite direction.

40 2. A piston having a cylindrical packer portion divided in an oblique plane into two sections, one section being rigid with the piston proper and the other section having limited longitudinal movement relatively to the first named section, the ends of the sections being adapted to abut in overlapping relation to separate the sections by cam action when the piston is moved in one direction.

45 3. A piston divided in a single oblique

plane into two sections and adapted to abut in such plane for separating the sections by 50 cam action when the piston is moved in one direction.

4. A piston divided in an oblique plane into two sections, and a rod secured to one of said sections, the other section having a 55 limited longitudinal movement relatively to the firstnamed section and rod, and the sections having a cam action between them for separating the sections when the piston is moved in one direction.

5. A piston composed of sections having cam surfaces to abut for separating the sections when the piston is moved in one direction, a rod secured to one of said sections, and a stop carried by the rod for limiting 65 the movement of the other section relatively to the aforesaid section.

6. A piston divided in an oblique plane into two sections, a rod secured to one of said sections, the other section having a longitudinal movement relatively to said section, and the sections having a cam action between them for separating the sections when the piston is moved in one direction, and a stop carried by said rod for limiting 70 the displacement of the second named section relatively to the firstnamed section.

7. A piston having a cylindrical packer portion, said piston, including the packer portion, being divided in an oblique plane into two sections so that the sections have a cam action between them for separating the sections, when the piston is moved in one direction, so that said packer portion fits the cylinder wall, a rod secured to one 80 of said sections, and a stop secured on said rod within said packer portion for limiting the longitudinal movement of the other section relatively to the firstnamed section.

In testimony whereof I have signed my 85 name to this specification in the presence of two subscribing witnesses.

SANFORD E. CLINE.
